(57) **CLAIM**

The ornamental design for an automotive body.

DESCRIPTION

FIG. 1—Is a perspective view showing both the front and left side of an automotive body, showing my new design.

FIG. 2.—Is a left side elevation view thereof;

FIG. 3.—Is a right side elevation view thereof;

FIG. 4.—Is a front elevation view thereof;

FIG. 5.—Is a back elevation view thereof; and,

FIG. 6.—Is a top view plan thereof.

In the drawings, the broken lines depict environmental subject matter only and form no part of the claimed design.
